US0D1023753S

(12) **United States Design Patent** (10) Patent No.: **US D1,023,753 S**
(45) Date of Patent: ** Apr. 23, 2024

(54) **CONTAINER WITH SURFACE INDICIA**

(71) Applicant: **The Procter & Gamble Company**,
Cincinnati, OH (US)

(72) Inventors: **Julian Richard John Gruzelier**, Vaud
(CH); **Emily Green**, London (GB);
Kristie Malivindi, London (GB)

(73) Assignee: **The Procter & Gamble Company**,
Cincinnati, OH (US)

(**) Term: **15 Years**

(21) Appl. No.: **29/809,000**

(22) Filed: **Sep. 24, 2021**

(51) LOC (14) Cl. **09-07**

(52) U.S. Cl.

USPC **D9/434**; D9/658

CLAIM

The ornamental design for a container with surface indicia, as shown and described.

DESCRIPTION

The patent or application file contains at least one drawing executed in color. Copies of this patent or patent application

publication with color drawing(s) will be provided by the Office upon request and payment of the necessary fee.

FIG. 1 is a front perspective view of a container with surface indicia, embodying our new design;

FIG. 2 is a front view of the container with surface indicia of FIG. 1;

FIG. 3 is a first side view of the container with surface indicia of FIG. 1;

FIG. 4 is a back view of the container with surface indicia of FIG. 1;

FIG. 5 is a second side view of the container with surface indicia of FIG. 1;

FIG. 6 is a top view side of the container with surface indicia bottle of FIG. 1; and

FIG. 7 is a bottom view of the container with surface indicia of FIG. 1;

FIG. 8 is a front perspective view of a container with surface indicia, embodying an embodiment of our new design;

FIG. 9 is a front view of the container with surface indicia of FIG. 8;

FIG. 10 is a first side view of the container with surface indicia of FIG. 8;

FIG. 11 is a back view of the container with surface indicia of FIG. 8;

FIG. 12 is a second side view of the container with surface indicia of FIG. 8;

FIG. 13 is a top view of the container with surface indicia of FIG. 8; and

FIG. 14 is a bottom view of the container with surface indicia of FIG. 8;

FIG. 15 is a front perspective view of a container with surface indicia, embodying an embodiment of our new design;

FIG. 16 is a front view of the container with surface indicia of FIG. 15;

FIG. 17 is a first side view of the container with surface indicia of FIG. 15;

FIG. 18 is a back view of the container with surface indicia of FIG. 15;

FIG. 19 is a second side view of the container with surface indicia of FIG. 15;

FIG. 20 is a top view of the container with surface indicia of FIG. 15; and

FIG. 21 is a bottom view of the container with surface indicia of FIG. 15;

FIG. 22 is a front perspective view of a container with surface indicia, embodying an embodiment of our new design;

FIG. 23 is a front view of the container with surface indicia of FIG. 22;

FIG. 24 is a first side view of the container with surface indicia of FIG. 22;

FIG. 25 is a back view of the container with surface indicia of FIG. 22;

FIG. 26 is a second side view of the container with surface indicia of FIG. 22;

FIG. 27 is a top view of the container with surface indicia of FIG. 22; and

FIG. 28 is a bottom view of the container with surface indicia of FIG. 22;

FIG. 29 is a front perspective view of a container with surface indicia, embodying an embodiment of our new design;

FIG. 30 is a front view of the container with surface indicia of FIG. 29;

FIG. 31 is a first side view of the container with surface indicia of FIG. 29;

FIG. 32 is a back view of the container with surface indicia of FIG. 29;

FIG. 33 is a second side view of the container with surface indicia of FIG. 29;

FIG. 34 is a top view of the container with surface indicia of FIG. 29; and

FIG. 35 is a bottom view of the container with surface indicia of FIG. 29;

FIG. 36 is a front perspective view of a container with surface indicia, embodying an embodiment of our new design;

FIG. 37 is a front view of the container with surface indicia of FIG. 36;

FIG. 38 is a first side view of the container with surface indicia of FIG. 36;

FIG. 39 is a back view of the container with surface indicia of FIG. 36;

FIG. 40 is a second side view of the container with surface indicia of FIG. 36;

FIG. 41 is a top view of the container with surface indicia of FIG. 36; and,

FIG. 42 is a bottom view of the container with surface indicia of FIG. 36.

In the drawings, the broken lines show portions of a container with surface indicia that form no part of the claim.
